Attorney.

UNITED STATES PATENT OFFICE

KARL FREIHERR ROEDER von DIERSBURG, OF GRAEFLING, NEAR MUNICH, GERMANY

FUR SUBSTITUTE FOR SKIING, ETC.

Application filed July 17, 1928, Serial No. 293,414, and in Germany December 20, 1927.

In order to prevent skis from slipping back when the wearer is mounting hills, it is usual to apply to the latter a tread of sealskin. Such skins are expensive and not very durable.

The object of the present invention is to provide a substitute for the sealskin, and the invention consists in the provision of a textile fabric to which wires, bristles, hair or like gripping tines are attached so as to form a pile having an inclined position relative to the fabric.

In the accompanying drawing,—

Fig. 1 is a sectional view of one form of my improved gripping fabric,

Fig. 2 is a similar view of another form of the fabric in an unfinished state, and

Fig. 3 is a sectional view of a portion of a ski runner to which is applied an anti-slipping covering material comprising the latter form of fabric in a finished state, the runner and its covering appearing in inverted position.

According to the invention the ski is provided upon its running surface A with an anti-slipping material in the form of a fabric b, to which wires, bristles, hairs or like tine-like grippers are attached, preferably to the weft threads c of the fabric, so as to form a permanently inclined pile a, the fabric being applied to the skis like the ordinary sealskin so as to allow of forward movement of the ski, while preventing it from slipping back.

Preferably, as shown in Figs. 2 and 3, two separate layers of fabric b and d' are employed, one of which is superposed on the other. This arrangement allows the pile forming wires or strands to be passed through the two layers at right angles to the surface, as shown in Fig. 2, the two layers being subsequently displaced relative to each other so as to tilt the pile, as shown in Fig. 3, and then fastened together to secure the pile in the inclined position.

The pile thus formed is not, like sealskin hairs, liable to fall out, but will wear right to the end of the life period of the skis.

Moreover, the tined gripping fabric embodying my invention formed of stiff and

more or less resilient gripping tines, unlike a gripping surface formed of mohair, plush or like pile fabric, ironed to give its pile an oblique set, will not lose its oblique angle of inclination, but will permanently retain such working angle, due to the character of the lines and to the fact that they are mechanically held at their correct working angle, so that at all times the gripping surface will act to allow the ski to slide forward while preventing it from slipping backward.

Having thus described my invention, what I claim is:

1. A ski having its runner face provided with an anti-slipping material comprising a textile fabric and comparatively stiff resilient tines attached to said fabric in the form of a gripping pile permanently inclined to the plane of the surface.

2. A ski having its running surface provided with anti-slipping material composed of two separate, superposed fabric layers carrying stiff resilient tines forming a gripping pile, said fabric layers being arranged and connected to dispose and hold said tines in an inclined position to the plane of the running surface.

In testimony whereof I have affixed my signature.
